UNITED STATES PATENT OFFICE

JOSEPH R. GIBSON, OF SHELBYVILLE, KENTUCKY.

COMBINED TIE HOLDER AND PRESSING DEVICE.

1,069,543.

Specification of Letters Patent.

Patented Aug. 5, 1913.

Application filed January 21, 1913. Serial No. 743,388.

To all whom it may concern:

Be it known that I, JOSEPH R. GIBSON, a citizen of the United States, residing at Shelbyville, in the county of Shelby and 5 State of Kentucky, have invented new and useful Improvements in Combined Tie Holders and Pressing Devices, of which the following is a specification.

An object of the invention is to provide a 10 device for holding ties and for pressing the same when the ties are not in use.

The invention embodies, among other features, a frame consisting of a plurality of connected plate sections, one mounted to 15 swing on the other, with a rack carried by one of the sections and adapted to support ties which depend between the sections, with means for exerting pressure against one of the sections to move the sections together 20 and firmly press the ties therebetween.

In the further disclosure of the invention reference is to be had to the accompanying drawings, constituting a part of this specification, in which similar characters of reference denote corresponding parts in all the 25 views, and in which:

Figure 1 is a perspective view of the device, showing the same in closed position to support and press ties; Fig. 2 is a side elevation of the structure disclosed in Fig. 1; Fig. 3 is a side elevation showing the article in open position, the ties having been removed therefrom; Fig. 4 is a front elevation showing the article in open position; Fig. 5 is a front elevation of the back plate section, the front plate section having been removed; Fig. 6 is a fragmentary enlarged vertical sectional view showing the attaching plate and screw for supporting the device on a 30 wall; and Fig. 7 is a fragmentary rear elevation of the attaching plate, the screw being shown in cross section in supporting position.

Referring more particularly to the views, 45 I employ a frame 10 consisting of a rear plate section 11 and a front plate section 12, a tie rack 13 being mounted to swing on the upper end of the rear plate section 11 and including an upright 14 mounted to swing 50 on a threaded pin 15 passing through the upper portion of the rear plate section 11, a thumb nut 16 being threaded on the pin to engage the upright 14 and bind the same with respect to the rear plate section in order 55 to secure the rack 13 in an adjusted po-

sition, a series of lateral supporting rods 17 being extended in a horizontal direction from the upright 14 as shown, to support a series of ties 18 adapted to depend between the rear plate section 11 and the front plate section 12. 60

Bearings 19 are secured to the front plate section 12 to support a member 20, the said member being preferably formed of a single piece of material such as spring-like wire 65 and bent in a U-shaped form to provide a handle 21, a pin 22 being journaled in the bearings 19 in order to properly support the member 20 on the front plate section 12, as will be hereinafter more fully disclosed, the 70 free ends of the handle being bent to form hooks 23 having pivotal connection with headed pins 24 secured in the rear plate section, the said hooks, however, being removable from the said pins when it is desired to 75 insert ties between the front and rear plate sections.

The medial portions of the handle 21 are coiled to provide springs 25 which loosely encircle the pin 22, thus supporting the 80 member 20 in a swinging position on the front plate section, as will be seen by referring to Figs. 1 and 4. Now it will be apparent that when the member 20 is in the position shown in Fig. 3, the front and rear 85 plate sections being in spaced relation, or in what may be termed semi-open position, and an upward pull is exerted on the handle 21, the resultant action of the springs 25 will cause the front plate section to move upwardly and slightly toward the rear plate section until the two plate sections are arranged in the position shown in Fig. 2, and when the handle 21 is pressed farther upwardly, the tension exerted by the springs 90 95 will cause the plate sections to move together and press the ties 18 therebetween, the upper end of the handle being secured in closed position by a securing strap 26 mounted to 100 swing on the front plate section 12.

The lower ends of the front and rear plate sections 11 and 12 are connected by suitable chains 27 as shown and in order to permit of supporting the entire device on a wall 105 28, disclosed in Fig. 6, an attaching plate 29 is secured to the rear face of the rear plate section 11, the said rear plate section being provided with a cut-away portion 30 adapted to register with a bayonet slot 31, 110 formed in the plate 29, so that when a head-

ed screw 32 is secured in the wall 28 as shown, it is only necessary to apply the device to the wall so that the headed screw will pass through the enlarged portion of 5 the slot 31 and then when the device is released the screw will pass into the restricted or smaller portion of the slot to prevent the disengagement of the device from the screw, this being accomplished by having the head 10 of the screw larger than the restricted portion of the slot, and thus the device will be supported on the wall 28 and cannot accidentally become detached therefrom. Now when it is desired to press ties between the 15 plate sections 11 and 12, the handle 21 is first disengaged from the securing strap 26 and will then assume the semi-open position disclosed in Fig. 3. The hooks 23 are detached from the pins 24 and the front plate 20 section swung downwardly and away from the rear plate section. The ties 18 are now placed upon the rack 13 by hanging the same upon the supporting rods 17 and when this has been accomplished the front plate section 25 is swung upwardly and the hooks 23 are reengaged with the pins 24 so that the ties 18 will depend between the front and rear plate sections. Now when the handle 21 is swung upwardly the front plate section will 30 be carried therewith until the front plate section lies adjacent to the rear plate section as shown in Fig. 2 and as an additional upward pressure is exerted on the handle 21, the springs 25 will exert a tension on 35 the hooks 23, thus causing the front and rear plate sections to move toward each other and press the ties therebetween. When the handle has been moved to its 40 uppermost distance it will be received beneath the securing strap 26 and locked in closed position, and the ties 18 depending between the front and rear plate sections will be pressed therebetween by the tension of the springs 25 tending to press the front 45 and rear plate sections together.

It will be apparent that with a device of the character described a large number of ties can be arranged to depend from the 50 rack and lie between the front and rear plate sections and the ties will not only be supported by the device but will also be pressed and retain their shape. It will be further apparent that various departures can be made from the construction disclosed 55 in the drawings without departing from the spirit of the invention and that the primary object is to provide a device for supporting the ties and pressing the same

when not in use, the scope of the invention being defined in the appended claims. 60

Having thus described my invention, I claim:

1. In a tie supporting and pressing device, the combination with a front plate section, of a rear plate section, a spring-actuated member mounted to swing on the front plate section and having connection with the rear plate section, a rack adjustably supported on the rear plate section and adapted to support ties depending between the said plate sections, and a securing strap mounted to swing on the front plate section to be engaged by the said member and secure the same in locked position to clamp the depending portions of the ties between the said plate sections. 70

2. In a tie supporting and pressing device, the combination with a front plate section, of a rear plate section, a spring-actuated handle mounted to swing on the front plate section and having connection with the rear plate section for normally moving the sections together, a rack carried by the rear plate section and adapted to support ties having portions depending between the plate sections and adapted to be pressed therebetween when the said handle is in uppermost position on the front plate section, a strap for securing the handle in uppermost position on the front plate section, and chains connecting the lower ends of the said plate sections. 80

3. In a tie supporting and pressing device, the combination with a plurality of plate sections, of a member connecting the plate sections and having a portion thereof constituting an integral spring, the said member being adapted to move the said plate sections together and clamp ties therebetween. 90

4. In a tie supporting and pressing device, the combination with a plurality of plate sections, of a member connecting the plate sections and having a portion thereof constituting an integral spring, the said member being adapted to move the said plate sections together and clamp ties therebetween, and means for securing the member in locked position on one of the plate sections. 100

In testimony whereof I affix my signature in presence of two witnesses.

JOSEPH R. GIBSON.
